UNITED STATES PATENT OFFICE.

GEORGE H. DAVIS, OF WORCESTER, MASSACHUSETTS.

VELOCIPED.

SPECIFICATION forming part of Letters Patent No. 410,751, dated September 10, 1889.

Application filed July 2, 1888. Serial No. 278,810. (No model.)

To all whom it may concern:

Be it known that I, GEORGE H. DAVIS, a citizen of the United States, residing at Worcester, in the county of Worcester and State 5 of Massachusetts, have invented certain new and useful Improvements in Velocipedes, of which the following, together with the accompanying drawings, is a specification sufficiently full, clear, and exact to enable persons skilled in the art to which this invention app pertains to make and use the same.

The objects of my invention are, first, to provide a velocipede having its seat and pedal-shaft maintained in the same relation to each 15 other, while affording a yielding action when moving on uneven ground or pavements, wherein the spring which connects said seat-supporting frame to the main frame is arranged in a manner to sustain said seat-supporting frame in position laterally, while yielding up and down; second, to provide a velocipede wherein the guiding-handles, seat, and pedal mechanism have a general yielding action independent of the main frame, with 20 means, such as described, for adjusting the height or position of the handles in relation to the seat, and for affording connection with the guiding-fork, as hereinafter explained; third, to provide in a velocipede having an 25 auxiliary yielding frame for supporting the seat and pedal mechanism, and facilities for changing the relative speed and power between the pedals and driving-wheel, means, substantially as described, for sustaining the 30 yielding frame and pedal mechanism in lateral position, and a clutch-shifting device mounted in connection with the yielding seat-supporting frame and under convenient control of the operator from his position on the 35 seat.

Other minor objects and features of my invention will be understood from the following description.

The particular subject-matter claimed is 45 hereinafter definitely specified.

In the drawings, Figure 1 is a perspective view illustrating my invention as applied to a bicycle. Fig. 2 is a plan view showing my improved mechanism for connecting the pedal-shafts and driving-wheel. Fig. 3 is a vertical

section of the pedal-shaft, showing the lower end of the rod for shifting the clutches. Fig. 4 is a side view illustrating my invention, with the guiding-handles mounted in connection with the seat-supporting frame. Fig. 5 is a top view of the machine shown in Fig. 4. Fig. 6 is a front view of the seat-supporting frame, pedal-shaft, and guiding-handles.

In referring to parts, A indicates the main frame or backbone, forked at its rear part to 60 carry the journal-bearings of the driving-wheel axle D, and having its front end pivoted in suitable or well-known manner to the frame or guiding fork B, that carries the bearings of the steering-wheel G.

C indicates an auxiliary movable frame or standard disposed in substantially upright position and forked at its lower end to carry the bearings of the pedal-shaft E, which is arranged in transverse horizontal position 70 between its lower ends, while on its upper end the seat S is supported, preferably, by a telescoping extension-standard S', that can be retained at any adjusted position by the clamping devices or binder c. The auxiliary 75 frame C is independent from the main frame A, but is connected therewith by a spring F, attached to the back of the main frame A by clamping-bands f, that embrace the frame and spring, as shown, or in other suitable 80 manner. The rear end of the main leaf of the spring F is attached to the frame C, as at f', in such manner that said movable frame and parts connected therewith will be suspended and supported by the spring, while 85 the lower part of said frame C is confined by suitable guides in connection with an arm A', that depends from the main frame A, said guide in the present instance being an interengaging slot and lug, as illustrated at h. 90 The pedal-shaft E is provided at its respective ends with cranks E' and foot-pedals e, substantially such as are usually employed in velocipedes. The bearings for the pedal-shaft are sustained parallel with and at 95 proper distance from the bearings of the driving-wheel axle by brace-rods H, that extend from one bearing to the other, as indicated, and which permit the pedal-shaft to rise and fall with the movement of the seat- 100

supporting frame without changing the relative radial distance between the axes of the respective bearings. The pedals *e*, pedal-shaft *E*, and operating-gearing are, by the frame 5 *C*, maintained in constant relation or at given distance from the seat *S*, so that they will simultaneously rise and fall with the movement of the seat, following the flexure of the spring *F*.

- 10 The spring *F* is preferably made, as illustrated, with its main or upper leaf attached to the frame *C*, and with a lower leaf *F*², which is disposed as a brace for supporting said upper leaf, as shown. An adjustable stud or 15 threaded bearing *v* is arranged on one of the connected bands *f*, which serves as a support for the under leaf of the spring, and by means of which the tension of the spring can be increased or diminished by simply screwing 20 said stud or bearing up or down, as required. The spring *F* is made broad and flat, and of sufficient width to sustain the movable seat-supporting frame *C* against lateral displacement. The clamping-band *f* confines the 25 spring rigidly upon the main frame *A*.

The pedal-shaft *E* is best provided with two sprocket-wheels *I* and *J*, of varied diameter, each of which is mounted loose on said shaft and each provided with one half of the 30 clutches *I'* and *J'*, while a longitudinally-movable sleeve *K*, which carries the other half of the clutches *I'* and *J'*, is arranged upon the pedal-shaft between the two sprocket-wheels, which sleeve is splined or keyed to 35 rotate with the shaft, and either of the sprockets *I* or *J* can be thrown into and out of action by moving the sleeve to the right or left into engagement with either of the respective clutches.

40 The axle of the driving-wheel *D* is provided with two sprocket-wheels *d* and *d'*, of different sizes, which are respectively connected by suitable drive-chains *L* with the sprocket-wheels on the pedal-shaft, the smaller 45 sprocket-wheel *d'* on the driving-wheel axis being connected with the larger sprocket-wheel on the pedal-shaft, and the larger sprocket-wheel on the driving-wheel axis being connected with the smaller sprocket-wheel on the pedal-shaft, thus affording 50 facilities for variation of the power and speed transmitted to the driving-wheel by a given movement of the pedals, accordingly as the clutch *I'* or the clutch *J'* is thrown into engagement for operating the larger or smaller sprocket-wheel.

The shipper-rod *m*, for moving the sleeve *K*, is supported in bearings on the movable frame *C*. The lower end of said rod is offset 55 or cranked and is fitted to a groove or collar on the clutch-sleeve *K*, while its upper end is provided with a lever or handle *m'*, by means of which said rod can be conveniently oscillated. A suitable stop is provided at *m*² for retaining the rod at position of adjustment, with the clutch thrown either to the

right or to the left or at an intermediate position at which the clutches are uncoupled.

The brace-rod *H*, or one of them, can be provided with a right and left threaded 70 sleeve or coupling, as at *H'*, for effecting adjustment to bring the axis of the pedal-shaft and the driving-wheel parallel with each other; or, if preferred, said brace-rod may be made solid or without such adjusting- 75 coupling.

The main frame *A* is preferably trussed and strengthened by rods *a* and *a'*, which extend from near the respective ends of said main frame to the lower part of the dependent arm 80 or guide-bar *A'*. Said rods *a* and *a'* serve both for trussing and strengthening the frame, and also for maintaining the guide which confines the lower end of the movable frame *C* in proper position.

The handle-bar *M*, for moving the guiding-wheel fork *B*, may be attached directly to the top of said fork in the usual manner, as shown in Fig. 1. I prefer, however, the improved construction shown in Figs. 4, 5, and 6, where- 85 in the handle-bar *M* is supported on the movable auxiliary frame *C*, which carries the seat *S*, so that said handle-bar will rise and fall simultaneously with the movement of the seat and pedal mechanism in accord with the flex- 90 ure of the spring *F*. In this construction the frame *C* is provided with the forward extension *C'*, having at its front end a bearing-socket *C*², within which is supported and clamped by a suitable set-screw *c*³ an adjust- 95 able sleeve *N*, disposed in substantially up- 100 right position. Within this sleeve is a rotating shaft or stud *N'*, on the upper end of which the handle-bar *M* is fixed. The lower end of said shaft carries a cross-head *N*³, from 105 which rods *n* connect with a cross-head *N*², fixed on the upper end of the guiding-wheel fork *B*.

The upper end of the fork *B*, or foot of shaft *N'*, is preferably provided with a compensating joint, as at *b*, to give yielding action as the yielding seat-frame *C* and guiding-handles 110 rise and fall.

A strong spring *T* is provided for supporting the head of the fork above the compensating joint, and holding that part of the fork or standard at forward position, while allowing it to yield to the motion of the movable frame *C*. The spring *T* preferably consists of a flat metal spring fixed at its lower end 115 to the body of the fork, and having its upper end extending through an eye connected to the upper end or head of the fork-standard, as indicated.

The advantages of my improved construc- 120 tion are, that while the seat is maintained at uniform and constant distance from the pedal-shaft the auxiliary frame is supported and sustained from lateral displacement by the spring without other connection save the guide 125 *h*, thus making a light and simple construc- 130 tion which gives ample upward and down-

ward spring or yielding action for the comfort of the rider upon the seat, while it avoids the necessity of hinged side braceings that would interfere with the freedom of action and add undesirable weight to the machine.

The arrangement of the handle-supporting devices, as shown, affords ready adjustment in a simple and desirable manner, herein shown and described, and can be applied to other styles of velocipedes than bicycles such as herein illustrated—as, for instance, to tricycles or machines having pairs of rear wheels, as indicated by dotted lines, Fig. 5, or in which the mechanism can be arranged to operate in an equivalent manner to that set forth.

What I claim as of my invention, and desire to secure by Letters Patent, is—

1. In a velocipede, the combination, with the main frame, of an auxiliary yielding frame carrying the seat and pedal-shaft, supported upon and connected with said main frame only by a spring that sustains the parts in position laterally while supporting the weight of said auxiliary frame, together with the pedal mechanism and rider upon the seat, and a guide (or guides) that retains the lower part of said auxiliary frame in proper relation, while it is free to rise and fall with the flexure of said spring.

2. In a velocipede, the seat, pedal-shaft, and chain driving-gearing mounted upon a movable auxiliary frame that maintains them at constant distance apart in relation to each other, in combination with the main frame, the attachment of said auxiliary frame to the main frame being formed by a spring, as F, that sustains the parts in lateral relation, while affording upward and downward yielding action, and braces that sustain the pedal-shaft at constant working position from the driving-wheel axis.

3. The combination, with the main frame A, of the auxiliary frame C, the flat curved spring F, connected by a hinge to the auxiliary frame and fixed on said main frame in the manner described to give vertical yielding support, while sustaining the parts laterally, the pedal-shaft E, carrying the cranks, and drive-chain gears supported in bearings fixed on the lower bifurcated end of said auxiliary frame, the seat S, having an extension-standard S', adjustable in the upper part of said auxiliary frame, and a clamp for retaining the said standard at position of adjustment, all substantially as set forth.

4. The combination, with the yielding auxiliary frame C, guiding-wheel fork B, and the handle-shaft N', supported in a bearing on said auxiliary frame, of the guiding-handles M, fixed to the upper end of said shaft, the cross-head N³ on the lower end of said shaft, the cross-head N² on the guide-wheel fork, and the link-rods n n, connecting the respective arms of said cross-heads, as and for the purposes set forth.

5. The combination, with the yielding frame C, having the forwardly-extended arm C', provided with a clamping-socket C² thereon, of the shaft-supporting sleeve N, extending through and longitudinally adjustable in said socket, the guiding-handles mounted on an upright shaft that extends through said sleeve and provided at its lower end with the cross-head N³, and a binder for clamping said sleeve at position of adjustment, substantially as shown, and for the purpose set forth.

6. The guide-wheel fork B, provided with an operating-head N², in combination with guiding-handles mounted on the yielding auxiliary frame, links that connect the parts for operation, and a compensating joint b, for the purpose set forth.

7. The compensating joint b and the joint-supporting spring T, in combination with the top or cross head N² of the guide-wheel fork and the guiding-connections, for the purpose set forth.

8. The combination of the driving-wheel D, mounted in bearings on the main frame A, the yielding auxiliary frame C, carrying the pedal-shaft E, the curved flat spring F, connecting said auxiliary frame with the main frame, the braces H, connecting the pedal-shaft and drive-shaft bearings, differential sprocket-wheels and drive-chains for transmitting power and motion from the pedal-shaft to the driving-wheel axis, clutches for connecting and releasing the pedal-shaft sprockets, the sliding clutch-sleeve K, the shipper-rod m, supported in bearings on said auxiliary frame and having a handle m', and a catch m², having detents for retaining said shipper-rod at positions of adjustment, all substantially as shown and described.

9. The main frame having the dependent arm A', in combination with the truss-rods a and a', extending from the front and rear ends of said frame and connected with the lower part of said arm.

10. The main frame having the dependent arm A', in combination with the auxiliary frame C, its guide h, and yielding supporting-spring F, substantially as set forth, and truss-rods a and a', extending from the front and rear ends of said frame and connected with the lower part of said arm.

11. The spring F, having its main leaf connected to the auxiliary movable frame C, and a second leaf disposed as a brace beneath its main leaf, in combination with the main frame A and auxiliary frame C, substantially as set forth.

12. The spring F, supported upon the main frame A, and having its main leaf connected to the auxiliary movable frame C, and a second leaf F², disposed as a brace beneath said main leaf, in combination with an adjusting-support v, for increasing or reducing the tension of said spring, substantially as set forth.

13. In combination, substantially as described, the frame A, guiding-fork B, wheels D and G, yielding frame C, seat S, handle-bar M, with flexible connections for operating said guiding-fork, the pedal-shaft E, with cranks and chain gearing for operating said driving-wheel D, the braces H, spring F, and guide A' h, for the purposes set forth.

Witness my hand this 28th day of June, A. D. 1888.

GEORGE H. DAVIS.
